UNITED STATES PATENT OFFICE.

GUSTAVOS HEIDEL, OF ST. LOUIS, MISSOURI, ASSIGNOR TO THE NATIONAL SELF-HEATING SAD IRON COMPANY, OF SAME PLACE.

BURNER FOR SELF-HEATING SAD-IRONS.

SPECIFICATION forming part of Letters Patent No. 415,716, dated November 26, 1889.

Application filed December 6, 1888. Serial No. 292,785. (No model.)

To all whom it may concern:

Be it known that I, GUSTAVOS HEIDEL, of the city of St. Louis, in the State of Missouri, have invented a certain new and useful Improvement in Burners for Self-Heating Sad-Irons, of which the following is a full, clear, and exact description, reference being had to the accompanying drawings, forming part of this specification, and in which—

10 Figure I is a side elevation of a sad-iron with my improved burner applied. Fig. II is a top view of the burner.

This invention relates to the construction of a burner for self-heating sad-irons, the object being to construct such a device as will be noiseless and in which all the gases will be consumed and prevented from escaping in their passage from the jet to the commingling-tube.

20 To this end my invention consists in features of novelty hereinafter fully described, and pointed out in the claim.

Referring to the drawings, 1 represents the body of the burner. 2 represents the jet of the burner; 3, the commingling-tube; and 4 represents the drip-cup.

My invention relates particularly to the construction of the commingling-tube. It has a nose 5, that extends into the combustion-

chamber of the iron, and at the outer end of this nose are wings 6, that receive the gas from the jet and the oxygen necessary to supply combustion. The wings are formed on a flaring marginal flange 7 of the nose, forming a mouth-piece to the commingling-tube, and it will be understood that as the gas escapes from the jet and is directed into the commingling-tube the wings will prevent any portion of it escaping and will add to the amount of oxygen commingled with the gas and forced into the combustion-chamber; and it has been found in practice that these wings avoid the noise incident to this class of burner.

The sad-iron to which my burner is shown as applied is shown, described, and claimed in my application of even date herewith, Serial No. 292,786.

I claim as my invention—

The generating - burner consisting of the forwardly-projecting commingling - tube 3, formed with a nose 5 and flaring marginal flange 7, having the wings 6 and providing a mouth-piece to the tube, the body 1, and the jet 2, substantially as shown and described.

GUSTAVOS HEIDEL.

In presence of—

GEO. H. KNIGHT,
EDW. S. KNIGHT.
